STEREOPHONIC TO BINAURAL CONVERSION APPARATUS

Benjamin B. Bauer, Stamford, Conn., assignor to Columbia Broadcasting System, Inc., New York, N.Y., a corporation of New York

Filed Dec. 29, 1960, Ser. No. 79,246

9 Claims. (Cl. 179—1)

The present invention relates to sound reproducing systems and, more particularly, to stereophonic systems of this character in which means is provided for reproducing the sound binaurally in proper space perspective so as to insure a high degree of naturalness in the sound as heard by a listener.

Binaural and stereophonic techniques have been employed with considerable success in sound recording and reproduction to impart a sense of direction to the reproduced sound. In the binaural method, the sound is picked up with omnidirectional microphones installed in a sphere or baffle to simulate the ears of a human head and the signals from the microphones are reproduced with corresponding earphones. In the stereophonic method, the signals are picked up with highly directional microphones or with spaced apart microphones and are reproduced with corresponding spaced apart loudspeakers. Where, however, program material is picked up or recorded by one of these two techniques and is reproduced by the other, substantial distortion of space perspective occurs. For example, when program material that has been picked up or recorded stereophonically is reproduced binaurally, as by feeding "Left" and "Right" channel signals separately to each of two earphones, the extreme "Left" and "Right" signals, respectively, appear to originate directly outside the listener's ears, resulting in a gross distortion in space perspective.

It is an object of the invention, accordingly, to provide a new and improved sound reproducing system that is free from the above-noted deficiency of the prior art.

Another object of the invention is to provide new and improved sound reproducing systems of the above character in which stereophonic program material can be reproduced binaurally without substantial distortion of space perspective.

These and other objects are attained by causing binaural sound reproducing means terminating each channel of a stereophonic sound reproducing system to respond both to the program material transmitted by the corresponding channel, suitably modified, and to the program material transmitted by another stereophonic channel of the system, appropriately delayed in time. More particularly, the modification effected in each channel simulates the diffraction effect of the head of a listener located in the path of sound from one of the loudspeakers in a stereophonic array, while the time delay in the program material from the other channel corresponds to the interaural time delay for a listener with respect to sound from one of the loudspeakers in such an array. In this fashion, the original stereophonic program material can be reproduced binaurally with substantially the correct space perspective.

For a better understanding of the invention, reference is made to the following detailed description of several representative embodiments, taken in conjunction with the accompanying drawings, in which:

FIG. 1 is a graph of typical relations that are helpful in understanding the invention;

FIG. 2 is a schematic diagram of a system for reproducing stereophonic program material binaurally according to the invention; and

FIG. 3 illustrates schematically another embodiment of the invention.

In a conventional stereophonic sound system, sound is picked up by several microphones placed near the performers in a broadly spaced array and suitably distributed between a plurality of transmission channels usually two in number. If the program material is reproduced by a plurality of loudspeakers distributed in space in approximately the same way as the microphones, the sound pattern produced at the ears of a listener positioned in front of the loudspeakers will be similar to that produced at a corresponding location in front of the performers. In other words, each ear of the listener will receive sound pressure from each of the loudspeakers, much in the same manner as each ear of a listener in front of the performers will receive sound pressure from directions both to his left and right.

When, however, the outputs of "Left" and "Right" stereophonic channels are fed to earphones, respectively, "Left" and "Right" sounds appear to originate directly outside the observer's ears, respectively, so that a gross distortion in space perspective results.

This distortion is largely eliminated, according to the invention by suitably modifying the signal in each channel and cross-feeding energy between the channels so as to simulate the sound pressure conditions prevailing at the ears of a listener located in front of a pair of spaced loudspeakers connected to receive the outputs of the stereophonic channels. For a listener location at a position making an angle of, say, 45° with a pair of speakers in a stereophonic array, it can be shown that the sound pressures produced by the left speaker at the left and right ears of a listener vary with frequency relative to the sound pressure for a "head-on" situation approximately in the manner indicated by the dotted line curves 10 and 11, respectively, in FIG. 1. These curves are based on data reported in a paper by F. M. Weiner entitled "On the Diffraction of a Progressive Sound Wave by the Human Head," The Jour. ASA, 19, 143-146, January 1947. Similar curves obtain for the sound pressures produced by the right speaker of the array, except that the curves 10 and 11 in this case correspond to the relative pressures at the right and left ears, respectively.

It will be apparent that the sound from each of two speakers disposed in a stereophonic array does not arrive simultaneously at the ears of a listener located between and in front of them. On the contrary, there is a time delay resulting from the fact that the ears are spaced apart in the direction of propagation of the sound. For a listener located at the intersection of two lines each making an angle of 45° with a line through the two speakers in the stereophonic array (a preferred location for stereophonic listening), the time delay between the left and right ears of the listener can be taken to be .4 millisecond, corresponding to a projected interaural distance of 5.5 inches on the 45° line to one of the speakers.

Correct reproduction of stereophonic program material binaurally, therefore, can be achieved by modifying the signal from the "Left" channel, which is to energize the "Left" binaural sound reproducer, in the manner indicated by the curve 10 in FIG. 1; combining with it a signal derived from the "Right" channel, modified as indicated by the curve 11 in FIG. 1, and delayed in time approximately .4 second; and effecting a comparable modification of the signal from the "Right" channel with corresponding cross-feed of energy from the "Left" channel.

Actually, only frequencies below about one kilocycle need be so delayed since, at frequencies above this value, stereophonic perception appears to be a function largely of sound intensity.

A symmetrical network T capable of modifying stereophonic signals essentially in the manner described above is shown in FIG. 2. It comprises a first series arm in-

cluding a resistor 12 and an inductor 13 in series, a second series arm with a resistor 14 and an inductor 15, and a shunt arm including a capacitor 16 connected in shunt with a series combination including a resistor 17, an inductor 18 and a capacitor 19. The network defines a pair of signal transmission channels, one of which is adapted to receive at its input terminals 20 a first stereophonic signal E_L from a source 21 and to provide a binaural output at its output terminals 22, and the other of which has input terminals 23 adapted to receive a second stereophonic signal E_R from a source 24 and output terminals 25 at which a second binaural output appears. The output terminals 22 and 25 of the two transmission channels are connected to suitable binaural sound reproducing apparatus such as a pair of earphones 26_L and 26_R, respectively. As indicated by the arrows in FIG. 2, the signals E_L and E_R are connected in a series additive sense, and the polarity of the earphones is likewise in a series additive sense as indicated by the dots on the earphones 26_L and 26_R.

In a practical system for operation from low impedance program sources (say, 4 ohms or less) and to feed high impedance earphones (say, 2,000 ohms or more), the resistors 18 and 20 may be 60 ohms each, the inductors 19 and 21 8 millihenries each, the capacitors 23 and 26 3.0 microfarads and 3.8 microfarads, respectively, the resistor 24 30 ohms and the inductor 25 4 millihenries.

The solid curves 27, 28 and 29 in FIG. 1 illustrate the performance of the system shown in FIG. 2. The curve 29 indicates that the desired delay time is well achieved up to 1 kilocycle per second, which is the frequency range where delay is most effective. Above 1 kilocycle per second, the amplitude function is more important (curves 27 and 28) and it is seen that these curves approximate the theoretical curves 10 and 11 reasonably well. By making the network components variable, an adjustment of the desired action may be obtained.

In operation, the left channel of the network in FIG. 2 supplies to the left earphone 26_L an output signal that is a composite of the stereophonic signal E_L , modified in frequency response as indicated by the curve 27 in FIG. 1, and the stereophonic signal E_R , modified in frequency response as indicated by the curve 28 in FIG. 1 and delayed about .4 second in time (at least for frequencies up to about 1 kilocycle per second). Similarly, the right channel supplies to the right earphone 26_R an output signal that is a composite of the stereophonic signal E_R , modified in frequency response as indicated by the curve 27 in FIG. 1, and the stereophonic signal E_L , modified in frequency response as indicated by the curve 28 in FIG. 1 and also delayed about .4 second in time for frequencies below about 1 kilocycle per second. Accordingly, the sound patterns at the ears of a listener wearing the earphones 26_L and 26_R will approximate those obtaining with the listener located in front of a pair of loudspeakers energized in response to the stereophonic signals E_L and E_R , respectively.

It will be noted that the network not only provides a cross-feed with suitable frequency response and time delay characteristics, but also modifies the corresponding signal in a manner similar to that which is caused by the diffraction by the head of the listener. Also, with two identical "Left" and "Right" signals, the network of FIG. 2 will provide a flat transmission characteristic, corresponding to the 0° incidence response in FIG. 1.

For low impedance earphones (i.e., 5 ohms or less), it is more convenient to use the system shown in FIG. 3, which is the dual of that depicted in FIG. 2. Here, the earphones as well as the stereophonic program sources are connected in a parallel additive mode. In FIG. 3, the program source 21' supplies a signal E_L through a resistor 30 to a shunt network arm including the earphone 26_L' and a parallel circuit including a capacitor 31 and a resistor 32. Similarly, the program source 24' supplies a signal E_R through a resistor 33 to another

shunt network arm including the earphone 26_R' and a parallel circuit including a capacitor 34 and a resistor 35. The two shunt arms containing the earphones 26_L' and 26_R' are connected together by a conductor 36 and by a coupling including an inductor 37 in series with a parallel combination including a resistor 38, a capacitor 39 and an inductor 40.

In a practical case, the resistors 30 and 33 may be 300 ohms each; the resistors 32 and 35 50 ohms each; the capacitors 31 and 34 2.7 microfarads each; the inductors 37 and 40 9 millihenries and 11.4 millihenries, respectively; the resistor 38 100 ohms; and the capacitor 39 1.3 microfarads. The system response is essentially as depicted by the curves 27, 28 and 29 in FIG. 1.

The invention thus provides novel and highly effective means for reproducing stereophonic program material binaurally. By modifying each of the signals fed to the reproducers in the manner described above, the correct sound pattern may be produced at the ears of the listener for reproduction without distortion in phase perspective.

The several embodiments described above are intended to be merely illustrative and are susceptible of modification in form and detail within the spirit of the invention. For example, acoustical tubes with appropriate delay characteristics may be used instead of electronic circuits for modifying the sound pressure at one earphone of a binaural system as a function of the sound pressure at the other. Also, while the networks herein described provide a most efficacious means for converting a stereophonic program into a binaural program, a less complete network may also be used. For example, a network providing a frequency discrimination only, without delay as shown by curves 27 and 28 in FIG. 1, or a delay only as shown by the curve 29 in FIG. 1, can be used with similar effect. Moreover, it will be understood that the specific values of electrical constants mentioned above are merely exemplary and other values can be used within the skill of the art. The invention, therefore, is not to be limited to the specific structures described and illustrated herein but embraces all modifications thereof coming within the scope of the following claims.

I claim:

1. In a sound reproducing system, the combination of a pair of earphones, a pair of signal channels connected to energize said respective earphones, and means for effecting additive transfer with time delay of signal energy from each of said signal channels to the other, said time delay being of the order of the time required for sound to travel a distance equal to the distance between the ears of a listener.
2. In apparatus for reproducing stereophonically related signals binaurally, the combination of a pair of signal channels adapted to receive a pair of stereophonically related signals, respectively, and to provide a pair of binaurally related output signals, respectively, and means in each of said channels for modifying at least a part of the stereophonic signal received thereby and for effecting cross-feed of stereophonic information therebetween in accordance with a given time delay characteristic approximating the time required for sound to travel a distance equal to the distance between the ears of a listener.
3. Apparatus as in claim 2 for reproducing stereophonically related signals binaurally in which the stereophonic information time delay characteristic simulates the interaural time delay for a listener with respect to one of a pair of speakers disposed in a stereophonic array.
4. Apparatus as in claim 2 for reproducing stereophonically related signals binaurally in which the modification effected by the modifying means in each of the channels simulates the modification of sound pressure generated by a loudspeaker caused by diffraction by the head of a listener.
5. Apparatus as in claim 2 for reproducing stereophonically related signals binaurally in which the modi-

fying means in each of the channels effects a rise in frequency response above about 200 cycles per second.

6. Apparatus as in claim 2 for reproducing stereophonically related signals binaurally in which the modification effected by the modifying means in each of the channels simulates the modification of sound pressure generated by a loudspeaker caused by diffraction by the head of a listener, and the stereophonic information time delay characteristic simulates the interaural time delay for a listener with respect to one of a pair of speakers disposed in a stereophonic array.

7. In a sound reproducing system, the combination of a symmetrical T network having adjacent first and second series arms and a shunt arm therebetween, resistance and inductance means in each of said series arms, a pair of sound reproducer means shunting said first and second series arms, respectively, resistance, inductance and capacitance means in said shunt arm, capacitance means connected in parallel with said shunt arm, first network input means connected to a terminal of one of said series arms and to a terminal of said shunt arm, and second network input means connected to a terminal of the other of said series arms and to said terminal of the shunt arm.

8. In a sound reproducing system, the combination of 25 a network having first, second and third series arms and

first and second shunt arms between said first and second and said second and third series arms, respectively, resistance means in said first and third series arms, respectively, sound reproducer means in series with resistance and inductance in parallel in said first and second shunt arms, inductance means in series with resistance means, capacitance means and inductance means in parallel in said second series arm, first network input means including said first series arm and said first shunt arm, and second network input means including said third series arm and said second shunt arm.

9. Apparatus as in claim 2 for reproducing stereophonically related signals binaurally in which the modifying means is variable so as to enable adjustment of 15 the modification effected thereby.
